UNITED STATES PATENT OFFICE.

CHARLES F. ROPER, OF HOPEDALE, MASSACHUSETTS, ASSIGNOR TO C. F. ROPER & COMPANY, OF HOPEDALE, MASSACHUSETTS, A FIRM.

CONTROLLING AND REVERSING MEANS.

No. 888,744.

Specification of Letters Patent.

Patented May 26, 1908.

Application filed December 7, 1907. Serial No. 405,466.

To all whom it may concern:

Be it known that I, CHARLES F. ROPER, a citizen of the United States, and resident of Hopedale, county of Worcester, State of Massachusetts, have invented an Improvement in Controlling and Reversing Means, of which the following description, in connection with the accompanying drawing, is a specification, like letters on the drawing representing like parts.

This invention has for its object the production of novel and efficient controlling and reversing means, particularly adapted for use in connection with speed-controlling reversing propellers for boats.

Propellers of this type are mounted on a shaft rotated by a suitable motor, and by means of a sleeve-like member loose on the shaft and operatively connected with the propeller blades, the speed of the boat can be controlled and its direction of movement reversed without varying either the speed or direction of rotation of the shaft. Such an apparatus is shown in United States Patent No. 807,498, granted to me December 19, 1905, and my present invention is particularly well adapted for governing the reversing member or sleeve in such apparatus, though my present invention is not restricted to such particular apparatus nor, in fact, to apparatus of that general type.

I have so constructed and arranged the mechanism to be herein after described that the controlling lever may be securely locked at any point of its angular movement, and I have also devised a novel form of connection between the lever and the reversing member, with adjustable means for positioning the latter upon the lever.

The various novel features of my invention will be fully described in the subjoined specification and particularly pointed out in the following claims.

Figure 1 is a side elevation of controlling and reversing means embodying my present invention, with a sufficient portion of the motor-shaft and the reversing sleeve to be understood, the parts being shown in neutral position; Fig. 2 is a right-hand side elevation of the apparatus illustrated in Fig. 1; Fig. 3 is an enlarged longitudinal sectional detail on the line 3—3, Fig. 2, to be referred to; Fig. 4 is a cross-section, also enlarged, on the line 4—4, Fig. 1; Fig. 5 is a top plan

view, enlarged, of a part of the locking means for the controlling lever.

Referring to Figs. 1 and 2, a stand 1 is fixedly bolted or otherwise secured to the floor or other supporting object F, the stand having at one end laterally separated ears 2 through which is extended a fulcrum pin 3. A third and larger upright ear 4, having preferably a slot 5, is formed on the stand at one side thereof and parallel to one of the ears 2. The fulcrum pin 3 is long enough to project beyond the latter ear and passes loosely through a hole in an upright frame comprising rigidly connected arms 6 united at their upper ends by a segment 7, which has formed upon its front face two segmental rows or series of oppositely-faced teeth 8, 9, Figs. 1 and 5.

Referring to Fig. 5 it will be seen that the teeth 8 have straight faces parallel to but turned oppositely to similar straight faces 75 of the teeth 9, so that if the straight faces of two teeth, one in each series, be engaged simultaneously by a suitable locking member said member will be held positively from movement in either direction. Such a locking member will be described hereinafter.

The lower part of the frame 6 rests against the rear face of the ear 4 and has an elongated slot 10 to receive a clamping bolt 11 seated in the slot 5, so that when the bolt is 80 set up the frame and its segment 7 are rigidly held in fixed position relatively to the stand 1. A nut 12 on the rear end of the fulcrum pin 3 prevents disengagement of the segment frame therefrom. By loosening the 90 clamping bolt 11 the segment frame can be turned in one direction or the other on the pin 3 in order to bring the center of the segment opposite the point at which the controlling lever, to be described, is in neutral 95 position. Such capability for adjustment of the segment is very convenient if the supporting surface or floor F is inclined, or out of the horizontal.

A yoke 13 having open sockets or seats 14 in its opposite cheeks has a depending, lateral tubular foot 15 which loosely embraces the fulcrum pin 3 between the ears 2 of the fixed stand, the yoke having that one of its cheeks nearest the segment frame extended or elongated to form a controlling or operating lever 16, shaped at its upper end to form a hand-grip 17.

The lever has formed upon it longitudinal ribs or flanges 18 provided with opposite ears 19 between which is fulcrumed a locking member or arm 20, pivoted on a pin 21, the 5 arm for the greater portion of its length lying between the flanges 18.

At its upper end the arm is bent away from the hand-grip at 22, and a spring 23 is inserted between the part 22 and a depression 24 in the lever, see dotted lines Fig. 2, 10 the spring normally maintaining the lower end of the arm 20 pressed toward the adjacent face of the lever.

The arm has at its lower end a rearwardly extended enlargement 25 entering an aperture 26 in the lever opposite the segmental series 15 of teeth 8 and 9, and locking dogs or lugs 28, 29 are formed on the enlargement, one above the other and faced in opposite directions, 20 see Fig. 5.

The lug 28 is adapted to coöperate with the series of teeth 8, and the lug 29 with the series of teeth 9, so that when the lugs are in 25 operative position both series of teeth will be engaged and the lever 16 is positively held from swinging movement in either direction on its fulcrum 3.

By grasping the part 22 of the locking member 20 and the hand-grip 17 simultaneously and closing his hand the operator rocks 30 the member 20 on its pivot 21 and disengages the lugs 28, 29 from the segmental series of teeth 8, 9, thereby unlocking the lever 16 so that it can be swung in either direction to any desired extent.

Release of the locking member permits the spring 23 to act instantly and positively lock the lever at the particular point to which it may have been moved.

40 A very slight angular movement is provided for by the locking arrangement described, as the teeth of the two segmental series may be made quite fine while still serving to securely lock the lever in the desired position.

I have herein shown at 30 a portion of a rotatable shaft, which may be the motor shaft of a boat, arranged to be driven at a constant speed and in one direction, and upon the 50 shaft an externally-threaded reversing member shown as a sleeve 31, longitudinal movement thereof upon the shaft changing the speed or reversing the direction of movement of the boat, as in my patent referred to, 55 the sleeve being shown partly in section in Fig. 3.

In order to operatively connect the sleeve 31 with the controlling lever 16 I extend the sleeve loosely through a tubular carrier 32 60 having lateral trunnions 33 which rest and rock in the seats 14 of the yoke 13, so that while swinging movement of the lever rocks the yoke the carrier will be moved longitudinally of the shaft 30, swinging more or less on 65 its trunnions 33 as may be necessary. A de-

pending longitudinal fin 34 on the carrier slides in a slot 35 in the yoke, thereby obviating any tendency of the carrier to rotate.

Suitable split nuts 36 are screwed onto the sleeve 31 and up against the opposite ends of 70 the carrier, after which the nuts are clamped in place by bolts 37, thereby causing the sleeve and carrier to move as a unit and retaining the carrier in longitudinally adjusted position relatively to the sleeve. 75

By the means described the parts can be easily and quickly adjusted so that when the propeller blades are in neutral position the controlling lever will be at mid-position relatively to the locking segment, as shown 80 in Fig. 1.

A stuffing-box 38 surrounding the shaft 30 at the inboard end of the sleeve 31 is screwed onto the latter and clamped thereon, suitable packing 39, Fig. 3, keeping the box 85 tight around the shaft, so that any water traveling along the shaft cannot pass beyond the stuffing-box.

As the locking segment is adjustable on the pin 3 upon which the controlling lever 90 16 is fulcrumed it will be seen that the proper relation between the locking teeth and the lugs on the locking member or arm 20 will always be maintained.

By providing the yoke with an elongated 95 foot to embrace the fulcrum pin I overcome any tendency of the lever to twist as it is swung in one or the other direction, its path of movement being maintained constant and parallel to the face of the locking segment. 100

The apparatus is strong and durable, simple, easily adjusted to varying conditions, and readily operated to effect the desired control of the mechanism with which it is operatively connected. 105

Having fully described my invention, what I claim as new and desire to secure by Letters Patent is:—

1. A reversing lever, a manually-operated locking member mounted thereon and movable in unison with and also laterally relatively to the lever, oppositely acting lugs on said member, a segment having two series of oppositely-faced locking teeth on its face adjacent the lever, the lugs on the locking member coöperating simultaneously with teeth in both series, to lock the lever from movement in either direction, and a sleeve pivotally connected with said lever and operatively moved longitudinally by angular movement of the lever, lateral movement of the locking member relatively to the lever effecting engagement or disengagement of the lugs and the locking teeth. 115

2. In apparatus of the class described, a 125 reversing member, a controlling lever operatively connected therewith and having a fixed fulcrum, a manually-operated locking member carried by the lever and having oppositely acting lugs, and two segmental 130

series of oppositely-faced locking teeth concentrically arranged one above the other adjacent the path of movement of the lever, to coöperate simultaneously with the lugs 5 and lock the lever from movement in either direction.

3. A reversing member, a swinging lever operatively connected therewith and movable in a fixed path, said lever having an 10 opening, a segment having two rows of oppositely-faced locking teeth arranged concentrically on the face of the segment adjacent the opening in the lever, and a manually-released locking member mounted on and 15 movable laterally relatively to the lever and having oppositely acting lugs extended through the opening, to engage simultaneously teeth of both series and lock the lever from movement in either direction.

20 4. In apparatus of the class described, a fixed stand, a swinging lever fulcrumed thereon, a reversing member, a pivotal connection between it and the lever, a segment adjustably mounted on the stand in parallelism with the path of movement of the lever, two rows of oppositely-faced teeth on the face of the segment adjacent and parallel to the path of the lever, and a manually-governed locking member on the lever, to 25 operate with both rows of teeth and positively prevent movement of the lever in either direction.

5. A fixed stand having separated ears, and a fulcrum pin mounted therein, a yoke 30 having a transverse, tubular foot depending therefrom to embrace the pin between the ears, a swinging lever rigidly connected with the yoke, means to lock the lever from angular movement, a tubular carrier fulcrumed in the yoke, the fulcrum of the carrier being in parallelism with the fulcrum of the yoke, an externally threaded reversing sleeve extended loosely through the carrier, and nuts screwed on said sleeve and abutting 35 against the opposite ends of the carrier, to rigidly and adjustably connect the said sleeve and carrier.

6. A fixed stand having separated ears, a yoke fulcrumed on the ears and having a socket at right angles to its fulcrum, a tubular carrier having trunnions pivotally mounted in the yoke, a depending fin on the carrier to enter the socket and prevent rotative movement of the carrier in the yoke, a threaded reversing sleeve extended loosely 50 through the carrier, and clamp-nuts adapted to be set up on the sleeve against the ends of the carrier, combined with a lever connected with and to rock the yoke, and means to lock the lever in desired position. 60

7. A rotatable power shaft, an externally threaded sleeve through which said shaft is extended to rotate freely therein, a tubular carrier loosely embracing the sleeve, nuts on the latter adapted to be set up against 65 the ends of the carrier, to clamp the sleeve and carrier together, retaining the carrier in longitudinally adjusted position relatively to the sleeve, a reversing lever having yoke-arms, a fixed fulcrum for the lever, trunnions on the carrier, pivotally mounted in the yoke-arms parallel to the lever fulcrum, to effect longitudinal movement of the sleeve upon the shaft by swinging movement of the lever, and manually-controlled means 70 to lock the lever at any point in its path of movement. 75

8. A fixed stand having separated ears, a yoke fulcrumed on the ears and having a socket at right angles to its fulcrum, a tubular carrier having trunnions pivotally mounted in the yoke, a fin on the carrier to enter the socket and prevent rotative movement of the carrier in the yoke, and a reversing sleeve moving in unison with the carrier 80 combined with a lever connected with and to rock the yoke. 85

In testimony whereof, I have signed my name to this specification, in the presence of two subscribing witnesses.
